UNITED STATES PATENT OFFICE.

CHARLES E. BYRNE, OF CHICAGO, ILLINOIS.

DESIGN FOR A PIANO CASE.

Application filed May 7, 1928. Serial No. 26,592. Term of patent 14 years.

To all whom it may concern:

Be it known that I, CHARLES E. BYRNE, a citizen of the United States, residing in the city of Chicago, in the county of Cook and the State of Illinois, have invented a new, original, and ornamental Design for Piano Case, of which the following is a specification, reference being had to the accompanying drawings, forming a part thereof.

In the drawings:—

Figure 1 is a perspective view of a piano embodying my design, showing the front and one end of the case.

Figure 2 is a perspective view of said piano showing the rear and the other end of the case.

I claim:—

The ornamental design for a piano case substantially as shown.

In testimony whereof, I have hereunto set my hand at Chicago, Illinois, this 4th day of May, 1928.

CHARLES E. BYRNE.
